UNITED STATES PATENT OFFICE.

BERTIE FRANCIS DELK, OF MACON, GEORGIA.

D-HANDLE-FINISHING MACHINE.

1,262,183.

Specification of Letters Patent.

Patented Apr. 9, 1918.

Application filed August 13, 1917. Serial No. 185,980.

To all whom it may concern:

Be it known that I, BERTIE F. DELK, a citizen of the United States, residing at Macon, in the county of Bibb and State of Georgia, have invented a new and useful D-Handle-Finishing Machine, of which the following is a specification.

The present invention relates to a wood-working machine having novel and improved means for cutting off and finishing or trimming the end of an article, such as the handle for a shovel, spade or similar implement.

The present improvements are designed especially for finishing the outer side of the handle grip, whereby it is rounded longitudinally and transversely to accommodate the hand.

Another object of the invention is the provision of novel means for receiving and holding the handle or article ready for the finishing operation.

A further object is the provision of a special cutter and mounting therefor to trim the handle grip effectively.

A still further object of the invention is the provision of other means for holding the handle and carrying it after the grip finishing cutter has done its work.

The invention also has for its object the utilization of the foregoing features in combination whereby they cooperate and interact for accomplishing the desired results satisfactorily.

With the foregoing and other objects in view, which will appear as the description proceeds, the invention resides in the combination and arrangement of parts and in the details of construction hereinafter described and claimed; it being understood that changes in the precise embodiment of the invention herein disclosed can be made within the scope of what is claimed, without departing from the spirit of the invention.

The invention is illustrated in the accompanying drawings, wherein:

Figure 1 is a fragmental side elevation of the machine illustrating the improvements.

Fig. 2 is a fragmental plan view thereof.

Fig. 3 is a fragmental front view.

Fig. 4 is an enlarged detail view of the improved cutter mechanism, portions being broken away.

Fig. 5 is a section on the line 5—5 of Fig. 4.

Fig. 6 is a plan view of the mechanism shown in Fig. 4.

Fig. 7 is an enlarged section on the line 7—7 of Fig. 1.

The machine embodies a suitable frame 1 in which there is mounted for vertical sliding movement, a carrier or shaft 2 for the handle or article to be operated on, said carrier being provided at its lower end with a forwardly extending yoke 3 having at its forward end an upstanding standard 4. The carrier 2 is provided with a forwardly projecting spur 5, while a spur 6 is slidable within the standard 4 in alignment with the spur 5, said spurs or gripping elements being adapted to bite the opposite ends of the grip portion of the blank handle 7, with the shank 8 of said handle projecting upwardly and centered by a forwardly projecting fork 9 into which the shank is moved when applied to the machine.

In order to force the spur or rod 6 rearwardly to grip and hold the handle between the spurs, an upwardly projecting lever 10 has its lower end pivoted, as at 11, to the standard 4, and said lever projects upwardly across the forward end of the spur 6 and carries an adjusting screw 12 adapted to abut against the forward heel end of the spur 6 when the lever 10 is swung rearwardly, so as to force the spur rearwardly against the handle. A suitable spring catch 12' is carried by the upper end of the standard 4 to snap into engagement with the lever 10 and hold it when said lever is forced rearwardly to project the spur 6 into engagement with the handle, thereby retaining the spur 6 in gripping position, so that the handle will be firmly held within the carrier. By releasing the catch 12', either manually or mechanically, this will release the lever 10 and spur 6, enabling the handle to be removed.

The carrier 2 is elevated after the outer side of the handle grip is finished, for other operations not forming a part of the present invention. Thus, a suitable cam 13 is mounted loosely upon a transverse shaft 14 journaled to the frame below the standard 4, and said cam is under the yoke 3 for raising the carrier at the proper time. The shaft 14 rotates continuously during the operation of the machine, and a cam controlled clutch is employed for connecting the cam 13 with the shaft at the proper moment to give said cam a complete rotation.

Thus, the cam 13 has a clutch hub 15 with which a clutch member 16 is engageable, said clutch member being feathered upon the shaft 14 and continuously rotated thereby, the shaft 14 having a sprocket wheel 17 connected by a sprocket chain 18 with a sprocket wheel 19 secured upon the drive shaft 20 of the machine. A depending lever 21 has its upper end pivoted to the frame in any suitable manner, and its lower end engages an annular groove of the clutch member 16, the lever 21 being connected by a link 22 with the arm 23 of a rock shaft 24 carried by the frame and having another arm 25 engaged at the proper moment by a cam 26 carried by a cam disk 27 secured upon a longitudinal shaft 28 geared, as at 29, with the drive shaft 20, the shaft 28 being rotated at a much slower speed than the shaft 20. The shaft 28 makes one complete rotation for each cycle of operation. The carrier 2 has rearwardly extending lugs 30 engageable with cam flanges 31 projecting from the forward face of the cam disk 27, whereby after the carrier 2 is raised by the cam 13, the forward ends of the flanges 31 engage said lugs, thus moving the carrier downwardly to return it to its starting position, during which returning movement of the handle with the carrier, the handle can be operated on by other finishing means (not shown). When the cam 26 contacts with the arm 25, and swings it outwardly, the link 22 is pushed by the arm 23 to swing the lever 21 and bring the clutch member 16 into engagement with the clutch hub 15 and holding it so engaged, whereby the cam 13 completes one revolution, the arm 25 then being released, so that a spring 21 then returns the parts to normal position and disengages the clutch member 16 from the clutch hub 15 with the cam 13 in normal idle position, the carrier 2 having been raised and then supported by the cam flanges 31.

Coming to the improved finishing mechanism for the outer side of the handle grip, the same embodies a guide 32 having the parallel vertical longitudinal side plates 33 connected at their rear ends by the end wall 34 provided with an upper recess 35 for receiving the spur 5 when the carrier 2 is lowered for starting position. A U-shaped abutment 36 is secured to the wall 34 in register with the recess 35 to accommodate the spur, and adapted for the abutment thereagainst of the rear end of the handle grip when the handle is placed into the machine. The guide 32 is seated upon a shelf 37 with which the frame is provided, and can be secured thereon by means of bolts 38 or the like.

Carried by the guide 32 is a device for temporarily holding and positioning the handle when introduced, said means em-

bodying an arm 39 having one end mounted, as at 40, between the side plates 33 of the guide 32, and provided at its free end with an upturned portion 41, said arm 39 and portion 41 being at one side of the guide 70 within the same, and the portion 41 having a handle seat 42 projecting inwardly therefrom. The arm 39 is further provided near its free end with a depending extension 43 having a transverse T-head at its lower end 75 providing the outwardly and inwardly extending fingers 44 and 45, respectively. The finger 44 is intended for engagement with a depending catch or detent 46 pivoted at its upper end, as at 47, to one side plate 33, and 80 provided near its lower end with a rounded lug 48 for the engagement of the finger 44 when the arm 39 is raised to handle-supporting position, as seen in Fig. 1. The catch 46 is yieldably held in position by 85 means of a spring 49 connected thereto and to the frame, so that when the arm 39 is raised into active position, the finger 44 will snap into engagement with the lug 48, thus holding the arm 39 raised, but enabling said 90 arm to be forcibly swung downwardly, for which purpose said arm has an upwardly extending finger 50. The arm 39 is raised by the contact of the yoke 3 with the finger 45 when the carrier is raised to uppermost 95 position, thereby placing the arm 39 in holding position when the carrier has been raised, in which position the arm 39 will remain as the carrier is lowered, so as to be in place for receiving and positioning the 100 next handle.

The cutter for trimming the outer side of the handle grip is carried by an arcuate slide 51 having the side plates 52, said slide mounted for curvilinear sliding movement 105 within the guide 32, and the side plates of said slide and guide having interengaging curved tongues and grooves 53 for guiding the slide for movement in the desired arc to trim the handle grip with a longitudinal 110 curvature. The cutter 55 is curved and suspended within the rear end of the slide 51, the ends of the cutter having outstanding lugs 54 overhanging the side plates 52. The lugs 54 are clamped on the plates 52 by bolts 115 56 extending through slots 56^a in the lugs and the lugs seat on adjusting studs 56^b which can be adjusted to adjust the position of the cutter relatively to the slide 51 in connection with the adjusting screws 56^c and bearing against the front edges of said lugs carried by the plates 52. Said cutter is curved transversely of the slide and is of concaved form in edge view, one edge of the cutter being sharpened to shave the 115 corners of the handle grip off. A yoke 57 connects the plates 52 near the cutter to render them rigid against the shoulders or lugs 54. The cutter 55 is curved to give the handle grip the desired transverse curva- 13

ture. The standard 4 projects upwardly within the cutter slide 51, said slide being slotted so there is no interference between the movement of the standard 4 and slide 51, the slide 51 being normally moved forwardly to retracted position with the cutter 55 immediately in rear of the standard 4 below the spur 6.

The actuating mechanism for the slide 51 embodies a U-shaped link 58 having its terminals pivoted to the plate 52 within the forward end of the slide 51, so that said link can move astride the lever 10 and standard 4 when moved rearwardly with the slide 51, there being a longitudinal slot between the side portions of the slide and link extending to the remote ends thereof for accommodating the standard 4 and lever 10 which project upwardly through said slot. The closed forward end of the link 58 is pivoted to an upstanding arm 60 secured to a transverse rock shaft 61 carried by the forward portion of the frame and provided with a downwardly projecting arm 62 fastened thereto, while an arm 63 is mounted loosely on the rock shaft 61 adjacent to the arm 62 and has lugs or ears 64 to move astride the arm 62, thereby providing a clutch for connecting the arm 63 and arm 62. A lever 65 fulcrumed to the frame at one side between its ends has one arm engaging a groove 66 of the hub of the arm 63, and a pushrod 67 is connected to the other arm of the lever 65 and is slidably carried by the frame, being provided with a roller 68 to be engaged by the cam 69 carried by the cam disk 27. When the cam 69 engages the roller 68, this pushes the rod 67 and swings the lever 65 to move the arm 63 into engagement with the arm 62 to swing the latter with the arm 63. The arm 63 is continuously oscillated during the operation of the machine, and for this purpose a gear wheel 73 meshing with a gear wheel 74 secured upon the drive shaft 20, is connected by a connecting rod 75 with the arm 63. When the cam 69 engages the roller 68 it moves the arm 63 into engagement with the arm 62 when in rearwardly swung position, and the cam 68 holds the arm 63 in engagement with the arm 62 until they have been moved forwardly and then rearwardly, at which time the arm 63 is released from the arm 62 by the spring 70 connected to the lever 65, the cam 69 having moved past the roller 68. Thus, the forward and rearward movement of the arm 62 with the arm 63, will swing the arm 60 rearwardly and then forwardly, thereby advancing the cutter slide 51 for the cutting operation and retracting it.

When the cutter slide is advanced to trim the handle grip, the lever 10 is pushed rearwardly to grip the handle 7 between the spurs 5 and 6, this being accomplished by an upstanding lug 71 carried by the closed

end of the link 58 and having an adjustable screw 72 to contact with the upper terminal of the lever 10 and moved rearwardly when the slide 51 is completing its rearward movement.

The operation of the mechanism is as follows: Normally, the slide 51 is retarded forwardly, the lever 10 swung forwardly and the spur 6 moved forwardly slightly, the cam 13 in the position seen in Fig. 1, and the handle-holding arm 39 in raised position, being held by the catch 46. The operator then introduces the handle 7, placing the same in a vertical longitudinal plane with the rear portion of the handle grip seated on the seat 42 against the portion 41 of the arm 39 and in abutment with the abutment 36, the shank 8 being placed in the fork 9. This will hold the handle in proper position, and the finger 50 of the arm 39 will project upwardly in the path of one side plate 52 of the slide 51. The operator then starts the machine by throwing in a clutch (not shown) to start the rotation of the drive shaft 20, as will be readily understood and the cam 69 in engaging the roller 68 will move the arm 63 into engagement with the arm 62, thereby swinging said arm 62 forwardly then rearwardly. Therefore, the arm 60 will first be swung rearwardly to move the link 58 and slide 51 rearwardly, and the cutter 55 is, therefore, moved longitudinally along the handle grip underneath the same from its forward to its rear end. The transverse curvature of the cutter 55 with respect to the slide 51 will trim off the corners of the handle grip, and the curvilinear movement of the slide 51 will give the handle grip the desired longitudinal curvature, the cutter 55 moving under the abutment 36 in completing its movement, as seen in Fig. 4. During the rearward movement of the slide 51, its contact with the finger 50 forces the same rearwardly, thereby forcing the arm 39 downwardly, and releasing it from the catch 46, so that said arm 39 will drop downwardly out of the way, thus removing the portion 41 and seat 42 from the handle so as not to interfere with the movement of the cutter and slide. The arm 39, however, serves to hold the handle in place until the cutter 55 has started its cutting action on the handle, the pressure of the cutter against the handle forcing it rearwardly against the abutment 36 and spur 5, so that the arm 39 is no longer needed. When the slide 51 completes its rearward movement, the screw 72 contacts with the lever 10 and swings it rearwardly to force the spur 6 into engagement with the handle, thus firmly holding the handle between the spurs 5 and 6, the lever 10 being held by the catch 12. The handle is thus gripped and held as soon as the cutter 55 completes its movement, the 130

slide 51 being returned by the return movement of the arms 62 and 63, after which the slide 51 remains stationary until the cycle of operation is completed, the cam 69 having moved past the roller 68. After the lever 10 has been moved to grip the handle within the carrier, the cam 26 swings the lever 25, thereby throwing the clutch member 16 into engagement with the clutch hub 15, where-
10 by the cam 13 will be given a complete rotation, thereby raising the carrier, which will elevate the handle with it. This upward movement of the carrier can be started during the return movement of the slide 51, since there will be no interference therebe-
15 tween, and after the carrier is raised, the lugs 30 thereof are engaged by the cam flanges 31, which will support and lower the carrier so that the handle can be operated on
20 by other finishing means (not shown). When the carrier is raised, the yoke 3 there-
of in contacting with the finger 45 will raise the arm 39 back into engagement with the catch 46, so that said arm will be in position
25 to receive the next handle after the carrier 2 has been lowered to normal starting position and the completed handle removed by releasing the catch 12' from the lever 10, thus enabling the handle to be removed
30 easily. When the carrier has been returned to normal lowered position, the cycle of operation is completed, and then repeated, as above described, after the finished handle is removed and a new blank handle inserted.
35 Having thus described the invention, what is claimed as new is:

1. A finishing machine embodying a guide having an abutment for an article to be operated on, a slide movable in said guide, means for moving the slide back and forth to and from said abutment, a cutter carried by the slide to move across the end of the article, a holding member pivoted to the guide and having a seat for the end of said article, said member having means for moving it out of the way when the slide approaches the abutment, a catch for holding said member in operative position, and means for swinging said member to operative position.
40

2. A finishing machine embodying a carrier having means for holding an article carried by said carrier, means for moving the carrier, a cutter to operate on the article, means for bringing said holding means into operation when the cutter operates on the article, temporary holding means for the article moved out of the way when the cutter operates on the article, said temporary hold-
45 ing means being restored when the carrier is moved to carry the article with it.
50

3. A finishing machine embodying a carrier, holding means for an article to be operated on carried by said carrier, a slide movable back and forth, a cutter carried by
55

said slide to operate on the article, means for moving the slide back and forth, means movable with said slide for bringing said holding means into operation when the cutter operates on the article, temporary hold-
70 ing means for the article moved out of the way when the cutter operates on the article, a catch for holding the temporary holding means in operative position, and means for moving the carrier, the temporary holding
75 means being restored when said carrier is moved.

4. A finishing machine embodying a car-
rier, a guide, having an abutment, the car-
rier having opposite holding members, one 80
adapted to move adjacent to the abutment
and the other being movable to grip an
article placed adjacent to said abutment, a
slide movable in the guide, a cutter carried
by the slide to trim the article, means for 85
moving the slide back and forth, means mov-
able with the slide for operating said mov-
able holding member to grip the handle
when the cutter operates on the article, and
temporary holding means for the article 90
moved out of the way when the cutter op-
erates thereon.

5. A finishing machine embodying a car-
rier, a guide having an abutment, the carrier
having opposite holding members, one 95
adapted to move adjacent to the abutment
and the other being movable to grip an
article placed adjacent to said abutment, a
slide movable in the guide, a cutter carried
by the slide to trim the article, means for 100
moving the slide back and forth, means mov-
able with the slide for operating said mov-
able holding member to grip the handle
when the cutter operates on the article, a
temporary holding member pivoted to the 105
guide and having a seat for the article, said
temporary holding member being moved out
of the way by the slide, a catch for holding
the temporary holding member in operative
position, and means for moving the car-
rier, the temporary holding member being
moved to operative position when the car-
rier is moved.
110

6. A finishing machine embodying a guide having an abutment, a carrier having a por-
tion movable adjacent to the abutment and
another portion movable within the guide,
a holding member carried by the first men-
tioned portion of the carrier and movable
adjacent to the abutment, a movable hold-
ing member carried by the second mentioned
portion of the carrier, a slide movable with-
in the guide, a cutter carried by the slide
to move across the end of the article, means
for moving the slide back and forth, means
moved with the slide for moving said mov-
able holding member into engagement with
the article when the cutter moves toward the
abutment, a temporary holding member piv-
oted to the guide and having a seat for the
125
130

end of the article, said temporary holding member having means for moving it out of the way when the slide is moved toward the abutment, a catch for holding the temporary holding member in operative position, and means for moving the carrier, said temporary holding member being moved back to operative position when the carrier is moved.

In testimony that I claim the foregoing as my own, I have hereto affixed my signature 10 in the presence of two witnesses.

BERTIE FRANCIS DELK.
